United States Patent Office

Des. 183,191
Patented July 15, 1958

183,191

HAND WASHING AGITATOR

Carl Amm, Forchheim, Germany

Application July 10, 1956, Serial No. 42,196

Term of patent 7 years

(Cl. D49—1)

Fig. 1

Fig. 2

Figure 1 shows a front elevation of the hand washing agitator forming my new design; and

Fig. 2 is a top plan view thereof.

The dominant features of the design reside in the portions shown in full lines.

I claim:

The ornamental design for a hand washing agitator, substantially as shown and described.
